Ely V. Patterson.

UNITED STATES PATENT OFFICE

GIUSEPPE BIGANTE, OF WESTERLEIGH, STATEN ISLAND, NEW YORK

GARMENT SUPPORTER

Application filed April 16, 1932. Serial No. 605,622.

The present invention relates to new and useful improvements in garment supporters, and while the same has been herein illustrated as a man's garter, it is capable of embodiment in other forms, as will be herein-after described.

It is an object of the invention to provide a garment supporter which will readily adjust itself to those portions of the body to 10 which it may be applied in use.

A further object of the invention is to provide a garment supporter, which may be used to support the hose of a person, and at the same time may be, if desired, employed to retain undergarments in proper wearing 15 position.

A further object of the invention is to provide a garment supporter, which when certain parts thereof become damaged may 20 still be used.

It is a further object of the invention so to construct a garter that a cushioning pad is employed which pad is adjustable with respect to a limb encircling band.

25 Still a further object of the invention resides in the provision of a single plate adapted for attachment to a cushioning pad which plate provides for the attachment of the several detachable or disconnectable portions 30 of the garment supporter.

With the above and other objects in view, reference will be had to the accompanying drawing, in which,

Figure 1 is a view in elevation showing 35 the garment supporter employed as a hose supporting garter attached to one of the under garments of the wearer,

Figure 2 is a perspective view on an enlarged scale of the garter,

40 Figure 3 is a detail transverse sectional view,

Figure 4 is a detail vertical sectional view,

Figure 5 is a detail perspective view illustrating a modified form of the invention.

45 Referring more particularly to the drawing, the device comprises a limb encircling band 10 which may be of elastic webbing or any other desired material, and said band has a looped end 11 within which is carried 50 a metallic fastening member 12 herein illus-

trated as in the form of a wire loop having a stud receiving portion 13.

The reference character 14 designates a cushioning pad, and this pad is adjustable upon the limb encircling band 10. To provide for this adjustment, the pad 14 is slotted as at 15 and 16, and the limb encircling band is passed behind that portion between the slits 15 and 16. The limb encircling band has its opposite end secured to a metallic plate 17. 55 This plate 17 is provided with two slots 18 and 19 and the end of the limb encircling band is passed through these two slots and around the intermediate portion 21 thereof and said end is then secured to the body portion as at 20 all of which construction is best 60 illustrated in Figure 3 of the drawing.

By this construction it will be apparent that the metallic plate 17 is carried by the limb encircling band 10, and rests upon the 70 cushioning pad 14.

The metallic plate 17 has an extended portion 22 which carries a lug 23, and upon its upper end said plate is provided with a lug or button 24 and adjacent its lower end with 75 a similar lug or button 25. The lower end of the plate is provided with a slot 26 and mounted in said slot there is a looped strap 27, the lower end of which has a button or stud 28. The upper end of this strap 27 is looped as at 29 and carries two looped fasteners 30 and 31, of which the looped fastener 30 is the larger.

The device so far described is employed in 80 the following manner.

The hose which is designated A in the drawing is passed over the stud 28 and the looped fastener 30 is engaged therewith in the usual manner. The limb encircling band 10 is next passed around the limb of the wearer and engaged with the stud 23, the fastener 12 being employed for this purpose and the stud being engaged in the portion 13 thereof. With the parts in this position, it being understood that the cushion and pad 14 is so adjusted upon the limb encircling band 10 that it lies immediately behind the plate 17, the 90 hose will be supported and the wearing of the device will be comfortable.

95 In some instances it may be desired to con- 100

nect the garment supporter with an under-garment of the wearer and when so desired, a strap 35 is employed. This strap has a looped fastener 36 which is adapted to engage the stud 24 and upon its opposite end said strap carries a fitting 37 to which is secured a strap 38 carrying a stud 39. Also carried by the strap 38 there is a looped fastener 40 which is adapted to engage with the stud 39 as best illustrated in Figure 1 in order to fasten the strap 35 to the undergarment B of the wearer.

As thus far described, it is apparent that in addition to supporting a hose, the device 15 may be employed to maintain in proper position an undergarment of the wearer.

The stud 25, provides for attaching the member 27 to the plate 17 in case said member should become ruptured, and this is accomplished merely by engagement of the looped fastener 31 with said stud 25, the member 20 27 then depending from the stud 25 instead of from the slot 26.

In Figure 5, I have illustrated a modified 25 form of the invention, and in this figure the reference character 50 designates a belt which is adapted to encircle the waist of a wearer. The belt 50 is similar to the limb encircling member 10, and is adapted to pass 30 beneath a strap portion 51 formed in a cushioning pad 52. The cushioning pad 52 carries a depending strap member 53 which in turn carries a stud 54 with which a looped fastener 55 is adapted to engage.

35 Any number of the cushioning pads may be employed and any number of garments may be supported from the belt 50 merely by providing a cushioning pad for each garment to be supported from the belt.

40 From the foregoing it will be apparent that the present invention provides a new and improved garment supporter which may be used in many different connections, and which in each manner of use is comfortable in use.

45 Having thus described the invention, what I claim as new and desire to secure by Letters Patent is:—

1. A garment supporter comprising a limb 50 encircling band, a cushion pad threaded upon said band and adjustable therealong, a plate carried by one end of said band and adapted to engage said cushion pad to limit movement of the pad in one direction along said band, and a garment engaging and supporting member depending from said plate.

2. A garment supporter comprising a limb 55 encircling band, a cushion pad threaded upon said band and adjustable therealong, a plate carried by one end of said band and adapted to engage said cushion pad to limit movement of the pad in one direction along said band, a plurality of attaching studs carried by said plate, and a garment attaching member mounted in a slot in the lower portion of said plate and depending therefrom.

3. A garment supporter comprising a limb encircling band, a cushion pad slidable along said band, a plate carried by one end of said band and with which the cushion pad is adapted to engage to limit movement of the pad in one direction along said band, a lateral projection extending from one edge of said plate, a stud carried by said projection, and means carried by one end of said limb encircling band for engagement with said lug. 75

4. A garment supporter comprising in combination, a limb encircling band, a cushion pad carried thereby and adjustable therealong, a plate secured to one end of said limb encircling band and adapted for engagement with the cushion pad to limit its movement along the band in one direction, means on the band and on the plate for interengagement to secure the band in limb encircling position, a garment engaging member permanently attached to said plate and a second garment supporter removably attached to said plate. 80 85

Signed at New York, New York, this 14th day of April, 1932. 90
